CLAIM

I claim the ornamental design for a printer media feeder, as shown and described.

DESCRIPTION

FIG. 1 is a perspective view of a printer media feeder showing my new design;

FIG. 2 is a front elevational view thereof;

FIG. 3 is a right side elevational view thereof, the left side elevational view being a mirror image thereof;

FIG. 4 is a top plan view thereof; and,

FIG. 5 is a bottom plan view thereof.

The broken line portions are shown for illustrative purposes only and form no part of the claimed design.
